UNITED STATES PATENT OFFICE.

WILLIAM T. JOHNSTON AND JAMES STEWART, OF GRAND RAPIDS, MICHIGAN.

CARPET-SWEEPER.

SPECIFICATION forming part of Letters Patent No. 670,513, dated March 26, 1901.

Application filed May 21, 1898. Renewed September 15, 1900. Serial No. 30,187. (No model.)

To all whom it may concern:

Be it known that we, WILLIAM T. JOHNSTON and JAMES STEWART, citizens of the United States, residing at Grand Rapids, in the county 5 of Kent and State of Michigan, have invented certain new and useful Improvements in Carpet-Sweepers; and we do hereby declare the following to be a full, clear, and exact description of the invention, such as will enable 10 others skilled in the art to which it appertains to make and use the same.

Our invention relates to improvements in carpet-sweepers; and its object is to provide the same with improved means for alternately 15 raising and lowering the sides of the pans adjacent to the brush, so that the pan in advance of the brush shall be close to the carpet and the pan at the rear of the brush will be elevated; also, to provide means for simultaneously adjusting both of the pans and the brush high or low for hard or soft carpet by shifting the bail from side to side of the case, and to provide the device with certain other 20 new and useful features, all of which are hereinafter more fully described, and particularly 25 pointed out in the claims, reference being had to the accompanying drawings, in which—

Figure 1 is an end elevation of a device embodying our invention, with a portion of the 30 case broken away to show the construction. Fig. 2 is a transverse vertical section of the same, showing the inner side of one end of the device; Fig. 3, a longitudinal vertical section of the same on the line 3 3 of Figs. 1 and 35 2, and Fig. 4 a detail showing one end of the device in vertical section on the line 4 4 of Figs. 1 and 2.

Like letters refer to like parts in all of the figures.

40 A represents the case, B the brush-shaft, and C the drive-wheels, all as usually made in carpet-sweepers.

D is the bail, provided with lugs D', projecting diagonally from the ends of the same 45 and arranged at such an angle thereto that when the bail is inclined to one side said lugs will project downward and engage the brush-hangers G, and when the bail is oppositely inclined the lugs will be out of engagement 50 with the hangers. The bail has a limited

horizontal movement on the case by being pivoted upon the ends of a rod E, extending across the case, near the top thereof, and rotative in vertical slots in clips F, attached to the ends of the case. Said rod has a slight 55 vertical movement in the clips to accommodate the horizontal movement of its ends in horizontal openings F' in the ends of the case. The rod E is bent twice at right angles near its ends, forming arms E', and its ends extend 60 through said horizontal slots in the case and are inserted in openings in the ends of the bail. The hangers G are provided with inwardly-projecting studs B', forming the journals for the brush, and extend upward therefrom and thence horizontally at right angles through openings in the case and have their inner ends extended upward inside the case and provided with vertically-slotted openings 65 to receive the ends of the rod E and permit the 70 hangers to move vertically on said rod. To prevent the brush-bearings from moving laterally and permit the hangers to thus move at their upper ends, lugs I I are struck up in the guard-bars, which lugs engage and hold 75 the respective edges of the hangers and allow them to slide vertically and rock therein. Springs L engage the studs B' and yieldingly support the hangers with their upper horizontal parts in contact with the bail ends. 80 Said springs are secured to the guard-bars by lugs I' I', struck up out of the guard-bars and engaging opposite sides of the spring and embracing the same. From the inner end of the hangers are extended diagonally outward 85 and downward the rigid arms G' G', to the lower ends of which arms the pans K are pivoted near their inner sides. The outer sides of the pans are pivoted to the movable ends of the horizontal arms M of the bell-crank levers pivoted to the case at J', substantially 90 opposite the ends of the arms G' and extending through the said case, from the outer ends of which pivots extend the vertical levers J. These levers are omitted at one end of the 95 case, one to each pan being sufficient to operate it. Springs L engage suitable pins K' in the bell-crank levers and yieldingly hold the pans in closed position.

The drive-wheels C are journaled on the re- 100.

spective ends of rods N, extending along the inner sides of the vertical walls of the case, and secured thereto by staples P P'. These rods are sprung out of line to prevent rotation thereof and to enable them to act as torsion-springs. These rods are also bent twice at right angles near the ends and extend through enlarged openings O in the ends of the case to permit said ends to move vertically. The case is thus supported on springs consisting of these rods, the ends of which form journals for the drive-wheels. These rods also operate as springs to press the drive-wheels against the brush-pulley B".

15 As propelling pressure is applied to the bail its journals move to the forward ends of the slots F'. It thus tilts the upper ends of the hangers forward and also lowers the forward pan close to the carpet at its inner edge 20 and raises the corresponding edge of the rear pan. When the motion of the sweeper is reversed, the described adjustment of the pans is reversed. Thus the leading pan is at all 25 times lowered and the other one raised at the side adjacent to the brush. When the bail is inclined to one side, as shown, the lugs D' are out of contact with the hangers, and the springs L' raise the hangers, together with both of the pans and also the brush, until the 30 hangers contact the rounded ends of the bail. This adjusts the machine "high" for sweeping soft carpets, and when the bail is oppositely inclined the lugs D' engage the hangers and adjust the brush and pans "low" for 35 hard carpets. It will be observed that such adjustment is in no wise affected or varied by any changes in the elevation of the end of the bail while in action, which is undesirable, such adjustment being best accomplished by downward pressure on the bail, which causes the torsion-springs formed by the rods N to yield and lower the case and contents. The bell-crank levers being pivoted substantially in the same line with the 40 pivots in the ends of the arms G', the pans readily turn on the latter pivots when the levers M are turned down against the action on the springs L to dump the pans.

45 By the described construction we are able to make the hangers G and diverging arms G' integral, and thus materially simplify the construction.

Having thus fully described our invention, what we claim, and wish to secure by Letters 55 Patent, is—

1. In a carpet-sweeper, a case, pans vertically movable at their inner sides, pivots supporting the outer sides of said pans, a rod journaled in the top of the case, and having its 60 ends extended downward and outward and horizontally movable in the case, a bail pivoted on the ends of said rod, and rigid diverging arms extending directly from the ends of said rod to the inner sides of the pans and attached thereto, substantially as described.

65 2. In a carpet-sweeper, a case having hori-

zontally-elongated openings in its ends, dust-pans vertically movable at their inner sides, pivots supporting the outer sides of said pans, a rod journaled in vertically-slotted clips and having its ends bent twice at right angles and sliding horizontally in said openings, a bail pivoted on the ends of said rod, and diverging arms connecting the sliding ends of said rod, with the inner sides of the dust-pans, substantially as described.

3. In a carpet-sweeper, a case, a bail horizontally movable relative to the case and having diagonally-projecting lugs at its ends, dust-pans having pivoted supports at their outer sides vertically movable at their inner sides, vertically-movable hangers supporting the brush and engaging the ends of the bail and the lugs on the same, springs supporting the hangers and diverging arms connected to the bail at their upper ends and pivoted to the inner sides of the dust-pans, substantially as described.

4. In a carpet-sweeper, a case, pans pivoted at their outer sides and vertically movable at their inner sides, a rod journaled in the top of the case and having its ends extended downward and outward through the ends of the case and horizontally movable therein, hangers supporting the brush and attached to the horizontally-movable ends of the rod, a bail pivoted on the same, and rigid diverging arms extending from the hangers to the inner sides of the dust-pans and attached thereto, substantially as described.

5. In a carpet-sweeper, a case, a bail journaled on a rod horizontally movable in the case, lugs on the bail, hangers supporting the brush and engaged by said lugs and the bail ends, and also having an upturned inner end having a slotted opening engaging said rod, springs supporting the hangers, and diverging arms attached to the hangers and supporting the inner sides of the pans, substantially as described.

6. In a carpet-sweeper, a case, dust-pans pivoted at their outer sides to said case, a bail having diagonal lugs on its ends and journaled on a rod horizontally movable in the case, hangers supporting the brush and having diverging arms supporting the inner sides of the pans and slotted upper ends engaging the rod and horizontal portions engaging the lugs, and springs supporting said hangers, substantially as described.

7. In a carpet-sweeper, in combination with a case and dust-pans, a rod journaled in the top of the case and having its ends extended downward and outward through the case and horizontally movable therein, a bail pivoted on said rod, diverging arms extending from the ends of said rod to the inner sides of the pans and pivoted to the same, bell-crank levers pivoted to the case opposite the pivots of said arms, and supporting the outer sides of the pans, substantially as described.

8. In a carpet-sweeper, in combination with

- the case, pans, and brush-shaft, a bail having journals horizontally movable in the case and also having diagonal lugs, hangers supporting the brush and engaging the said lugs and 5 journals, diverging arms attached to the hangers and pivotally supporting the inner sides of the pans, bell-crank levers pivoted to the case opposite the ends of said arms and pivoted to the outer sides of the pans and 10 supporting the same, and supporting-springs for the hangers and bell-crank substantially as described.
9. In a carpet-sweeper, a case, a rod extending across the top of the case and thence downward and outward through horizontally-elongated openings in the case, clips supporting said rod, a bail pivoted on the ends of said rod and having diagonal lugs, hangers supporting the brush and extending beneath the 15 bail and engaged by the same and also having an upwardly-extended portion having a slotted opening engaging said rod, means for yieldingly supporting said hangers, diverging arms pivoted to the inner ends of the 20 pans and supporting the same, and bell-crank levers pivoted to the case opposite the ends of said arms and having their horizontal arms pivoted to the outer sides of the pans and 25 supporting the same, substantially as described.
10. In a carpet-sweeper, the combination of a case, a bail horizontally movable on the case and having diagonal lugs on its ends, hangers engaging the bail and moved at its upper end 30 both vertically and horizontally thereby,
- guard-bars having lugs engaging the edges of said hangers, springs secured to the guard-bars and supporting said hangers, and diverging arms on the hangers pivoted to the inner sides of the pans and supporting the same, 40 and pivoted supports for the outer sides of said pans, substantially as described.
11. In a carpet-sweeper, a case, a rod extending across the top of the case and bent twice at right angles near its ends and extended 45 through the horizontally-elongated openings in the case, clips supporting said rod and having vertical slots, a bail pivoted on the ends of said rod and having diagonal lugs on its ends, hangers supporting the brush-shaft and 50 extending horizontally beneath the bail and engaged thereby and thence extending upward and provided with vertically-elongated openings engaging said rod, guard-bars having lugs embracing said hangers, springs attached to said bars and supporting the hangers, diverging arms on the hangers pivoted to the inner sides of the pans, bell-crank levers pivoted to the case opposite the pivots of said arms and also pivoted to the outer sides of 55 the pans and springs engaging said bell-crank levers, substantially as described.

In testimony whereof we affix our signatures in presence of two witnesses.
